UNITED STATES PATENT OFFICE.

EDWARD F. HOWE, OF WATERTOWN, MASSACHUSETTS.

DESIGN FOR A GUITAR-BODY.

SPECIFICATION forming part of **Design No. 27,560**, dated **August 24, 1897**.

Application filed February 18, 1897. Serial No. 624,056. Term of patent 14 years.

To all whom it may concern:

Be it known that I, EDWARD F. HOWE, a citizen of the United States, residing in Watertown, in the county of Middlesex and State of Massachusetts, have invented and produced a new and original Design for a Guitar-Body, of which the following is a specification, reference being made to the accompanying drawings, forming a part thereof.

10 Figure 1 of the drawings shows a perspective view of my new and original design for a guitar-body; Fig. 2, a longitudinal section on line $x x$, Fig. 1; and Fig. 3, a cross-section on line $y y$, Fig. 1.

15 The leading feature of my design consists in a guitar-shaped top having a longitudinal central swell and strings arranged in pairs extending from end to end of said swelled top.

a represents the top of the instrument, having a hole a' and a longitudinal central swell a^2 , and said top is made guitar-shaped.

b represents a bar rising from said top, over which the strings c' , arranged in pairs, pass, they extending from end to end of the top.

c represents the rim, and d the neck, having a head e .

I claim—

The design for a guitar-body as herein shown and described.

In testimony whereof I have signed my name to this specification in the presence of two subscribing witnesses.

EDWARD F. HOWE.

Witnesses:

B. J. NOYES,
HARRY O. ROBINSON.
